UNITED STATES PATENT OFFICE.

JOHN H. WEBER AND JAMES B. STURTEVANT, OF LOS ANGELES CALIFORNIA.

DESIGN FOR A SIGNAL-LIGHT FOR AUTOMOBILES.

59,439.

Specification for Design.

Patented Oct. 18, 1921.

Application filed August 17, 1920. Serial No. 404,274. Term of patent 3½ years.

To all whom it may concern:

Be it known that we, JOHN H. WEBER and JAMES B. STURTEVANT, citizens of the United States, residing at Los Angeles, in the county of Los Angeles and State of California, have invented a new, original, and ornamental Design for Signal-Lights for Automobiles, of which the following is a specification, reference being had to the accompanying drawing, forming a part thereof.

Figure 1 is a front elevation of a signal light for automobiles showing our new design, and

Fig. 2 is a side view thereof.

We claim:

The ornamental design for a signal light for automobiles as shown.

J. H. WEBER.

J. B. STURTEVANT.
